UNITED STATES PATENT OFFICE.

HARRY J. LEBHERZ, OF FREDERICK, MARYLAND.

BAG SUPPORT.

Application filed February 7, 1923. Serial No. 617,526.

To all whom it may concern:

Be it known that I, HARRY J. LEBHERZ, a citizen of the United States, and resident of Frederick, in the county of Frederick 5 and State of Maryland, have invented certain new and useful Improvements in Bag Supports, of which the following is a specification.

This invention relates to bag supports, 10 having reference more especially to means for suspending filter or strainer bags in operative relation to the mouths of crocks, milk cans, and similar vessels.

My invention has for its object to provide a bag support of simple, inexpensive 15 and durable construction that can be readily adjusted to and firmly mounted on vessels of different sizes; and also to provide such a device that can be readily collapsed and 20 securely held in small compass for convenience of packing and transportation.

Accordingly my invention comprises a bag support embodying novel features of construction and combinations of parts that 25 will be hereinafter described and claimed.

In the drawings—

Figure 1 is a perspective view of my improved bag support as in actual use.

Fig. 2 is a detail, enlarged, of the adjacent ends of two hoop segments and their associated supporting leg and bag engaging finger.

Fig. 3 is a similar view of the segments, leg and finger, together with the rivet, as 35 separated.

The bag support herein illustrated comprises a hoop 4 having thereon, in spaced relation to each other, up-standing members 5 designed to engage and suspend a 40 filter bag 6 or the like, said hoop having pivoted thereto supporting legs 7 that are provided at their basal ends with clamp hooks 8 adapted to be detachably applied to the rim of a crock or other vessel, as 9, 45 in order to sustain the hoop in elevated position with the bag depending centrally of the vessel.

In pursuance of my invention the hoop is composed of a series of assembled segments 50 of flat strip metal, each segment being provided at its respective ends with outwardly projecting transversely perforated lugs 10. The adjacent lugs of each pair of adjoining segments snugly embrace the perforated upper end of a leg 7 also prefer-

ably of flat strip metal, and such end is pivotally supported between the lugs by means of a rivet 11 extending through the perforations of the associated parts. This rivet, being flattened or spread at its free 60 end, binds the lugs frictionally against the interposed leg in such a manner that the leg is firmly held in any position to which it may be swung on its pivot, either toward or from the vertical axis of the hoop. The 65 leg is twisted slightly below the lugs, as at 12, to position its flat surface at right angles to the radial plane of the lugs, and the basal end of such leg is bent into hook-form to provide a clamp that can be readily 70 applied to the rim of the vessel. In the present instance the hoop comprises four segments, a corresponding number of supporting legs therefor being provided, but, of course, the number of segments and legs 75 may be varied without departure from my invention.

The bag engaging members 5 preferably correspond in number with the segments, each of said members comprising an up-standing finger piece of flat metal shaped to enter a grommet 13 in the bag and having a perforated basal portion 14 that is placed flatwise against the outer side of one of the lugs 10 and with its inner vertical edge 80 against the opposing face of the adjacent segment in such position that the perforation of the basal portion 14 receives the rivet 11 passing through the perforations of the lugs and leg. This rivet thus not 85 only effectually clamps the lugs against the interposed end of the leg, but it also secures the finger piece rigidly in place on the adjacent segment.

From the foregoing it will be seen that 90 the various parts of the device can be cheaply and readily constructed and assembled from flat strip metal; that the legs of the device by virtue of the special pivotal mounting described can be readily swung 100 on their pivots to accommodate crocks or vessels of different diameters within limits, and yet are firmly held by friction in adjusted positions; and that irrespective of the various adjustments of the legs the relative positions of the rigid bag-engaging members on the hoop remain unchanged.

It will also be seen that when the device is collapsed by swinging the legs inwardly beneath the loop, for convenience of pack- 110

ing and transportation, such legs, by their frictional mounting on the segmental hoop, remain securely in folded position.

I claim—

- 5 1. In a bag support, a series of segments assembled in hoop form, each segment having laterally-projecting end lugs, bag-engaging members mounted on and projecting above the segments, and a plurality of 10 legs of flat strip metal having their upper ends frictionally embraced by and pivoted to the paired lugs of adjacent segments, each of said legs being twisted below the lugs to position its flat surface at right 15 angles to the plane of the lugs.
2. In a bag support, a series of segments assembled in hoop form, each segment having laterally-projecting end lugs, a plurality of legs having their upper ends frictionally embraced by and pivoted to the 20 paired lugs of adjacent segments, and up-standing bag-engaging members secured to said segments.
3. In a bag support, a series of segments 25 assembled in hoop form, each segment having laterally-projecting end lugs, a plural-

ity of legs having their upper ends frictionally embraced by the paired lugs of adjacent segments, up-standing bag-engaging fingers laterally of the lugs, and pivot 30 means connecting and clamping together the associated lugs, leg and bag-engaging finger.

4. In a bag support, a series of segments of flat strip metal assembled in hoop-form, 35 each segment having perforated laterally-projecting end lugs, a plurality of legs of flat strip metal having their upper ends perforated and frictionally embraced by the paired legs of adjacent segments, up-standing 40 bag-engaging fingers each having a flat perforated basal portion applied to the outer side of one of said lugs and with its inner vertical edge bearing against the opposing face of the adjacent segment, and a rivet 45 passing through the perforations of the basal portion of each finger, its associated lugs and leg.

Signed at Frederick, in the county of Frederick and State of Maryland, this 3rd 50 day of February, A. D. 1923.

HARRY J. LEBHERZ.
